WINDOW STRUCTURE

Eric Sigfrid Persson, Malmo, Sweden

Application March 3, 1955, Serial No. 491,909

Claims priority, application Sweden March 23, 1948

1 Claim. (Cl. 160—34)

My present invention relates to a window structure for closing a window opening in the wall of a building for admission of light and air.

This application is a continuation-in-part of my U. S. application Ser. No. 60,127, filed November 15, 1948, for window structure, and which has now become abandoned.

It is an object of this invention to provide an improved window structure with two spaced glass panes in a single or double metal sash mounted for swinging movement in a rectangular frame to be mounted with two of its sides in vertical position and with its other two sides as bottom and top, respectively, in a window opening in the wall of a building for admission of light and air.

Another object of this invention is to provide an improved window structure of the aforesaid kind incorporating a Venetian or other blind mounted on the swingable metal sash inside its top so as to be lowered and raised in the space between the glass panes.

Further objects of this invention and advantages gained thereby will appear from the following description of a preferred form of the invention illustrated in the accompanying drawings in which:

Fig. 1 is a diagrammatic view of a window with frame and sash, in which the sash is mounted for swinging movement in the frame through an angle of about 180° about a median horizontal axis, the sash being shown as having been swung from shut position with bottom outwards and top inwards through a small angle to a ventilating position.

Figs. 2, 3 and 4 are cross sectional views on a larger scale taken substantially on the lines II—II, III—III and IV—IV, respectively, in Fig. 1, but with the sash in shut position, the sash being a double sash composed of an inner sash pivoted to the frame for swinging movement therein, and an outer sash hinged at bottom to said inner sash for swinging movement therewith and in relation thereto.

Figs. 5 and 6 are fragmental front views showing the lower right corner and the upper right corner, respectively, of the window as viewed from inside the building having in its wall the window opening closed by the window.

Fig. 7 is a fragmental sectional view taken substantially on the line VII—VII in Fig. 6.

Fig. 8 is a fragmental sectional view taken substantially on the line VIII—VIII in Fig. 7.

The rectangular window frame 10, which is to be mounted with two of its sides in vertical position and with its two other sides as bottom and top, respectively, in a window opening in the wall of a building, may be constructed from metal or from wood as may be desired. The sash, generally denoted 11 in Fig. 1, is to be furnished with two spaced glass panes 12 and 13 (Figs. 3—6) and preferably consists of a double sash composed of an inner sash furnished with the inner glass pane 12 and pivoted to the vertical sides of the frame 10 for swinging movement therein through an angle of about 180° about a

2

median horizontal axis, and an outer sash furnished with the outer glass pane 13 and hinged at bottom to the inner sash for swinging movement therewith and in relation thereto. Means for pivoting the inner sash to the vertical sides of the frame 10, and means for hinging the outer sash to the inner sash are provided but are not shown on the drawings and will not be described herein because such means of different constructions are well known in the art and do not form part of this invention.

10 The inner sash furnished with the inner glass pane 12 is composed of a one-piece bar of rolled or extruded metal, preferably aluminum, bent to U-shaped formation with rounded corners 14 (see Figs. 1 and 5) between its bottom portion 15 and integral legs 16 forming bottom and vertical sides, respectively, of said sash, and a straight sash top metal rail 17 extending between the free ends of said legs 16 and forming right angles with them (see Fig. 6) and being detachably secured at its ends to said free ends of said legs 16. The detachable sash top rail 17 has a depending flange 18 for hiding a blind, preferably a Venetian blind, to be mounted on said top rail 17 inside thereof and behind said depending flange 18 (Figs. 2 and 6), so that the blind may be lowered and raised in the space between the two glass panes 12 and 13. Recesses, preferably in the form of grooves, for receiving the edges of the inner glass pane 12 are provided in the inside of said U-formation comprising the inner sash bottom portion 15 and the integral legs 16, and in the free edge portion of the depending flange 18 of the inner sash top rail 17, said grooves being denoted 19 and 20, respectively, and shown in cross section in Figs. 2—4.

The outer sash furnished with the outer glass pane 13 is of a construction similar to that of the inner sash so far that also the outer sash is composed of a one-piece metal bar bent to U-shaped formation with rounded corners between its bottom portion 21 and integral legs 22 forming bottom and vertical sides, respectively, of the outer sash, and a straight outer sash top rail 23 extending between and detachably secured to the free ends of the legs 22 and forming right angles with them. Also the outer sash top rail 23 is provided with a depending flange 24, whereby the blind to be mounted on the inner sash top rail inside thereof will be housed between the depending flanges 18 and 24 of the inner sash and the outer sash, respectively. Grooves 25 and 26 for receiving the edges of the outer glass pane 13 are provided in the inside of the U-shaped formation comprising the bottom portion 21 and the integral legs 22 and in the free edge portion of the depending flange 24, respectively.

In the preferred form of the invention shown on the drawings the cross sectional shape of the inner sash top rail 17 is that of a hat section with a crown portion 17a and front and rear brim portions 17b and 30 respectively, and with a veil hanging from the front end of the front brim portion and forming the depending flange 18. The crown portion 17a forms a groove for receiving a mounting bar 27 of channel shape for a Venetian blind 28, as shown in Fig. 2.

60 In the preferred form of the invention the outer sash top rail 23 comprises a strip-shaped portion 29 fitting over the rear brim portion 30 of the hat section of the inner sash top rail 17, and a flange 31 projecting upwards from one longitudinal edge of said strip portion 29 for contact with the portion 32 of the inner sash top rail 17 forming the rear side of the crown of the hat section. The depending flange 24 projects from the other longitudinal edge of the strip-shaped portion 29.

Figs. 6 and 7 illustrate, by way of example, one form 70 of means for the fastening of the ends of the detachable inner sash top rail 17 to the free ends of the legs 16

of the U-shaped formation of the inner sash. Figs. 6 and 7 show the fastening at the right upper corner of the sash. The U-shaped formation of the inner sash is provided in its outside with a groove 33 (see Figs. 2, 3 and 4), and at the free end portion of each of the legs 16 there is inserted and secured in this groove 33 one leg 34 (Figs. 6 and 7) of an angle-shaped member whose other leg 35 projects towards the other leg 16. The top rail 17 is fastened to the leg 35 by screws 36.

The means for fastening the detachable outer sash top rail 23 between the legs 22 preferably comprises lugs 37 (shown in cross section in Fig. 7) projecting from the ends of the depending flange 24 into the grooves 25 at the free end portions of the legs 22 and fastened to them by screws 38.

On the outside of the portions of the legs 16 extending above the pivotal axis of the inner sash there are mounted preferably wooden ribs 39 (Fig. 3) for abutting corresponding abutments 40 on the inside of the vertical portions of the frame 10, and on the inside of the portions of the frame below said axis there are provided similar ribs 41 (Figs. 2 and 4) for abutting corresponding abutments 42 on the inner sash. The flange 31 projects up between the coating abutment means 32 and 42 of the inner sash top rail 17 and the top of the frame, respectively, whereby the outer sash will be safely held to the inner sash when shut.

The shown and described construction of the sashes unites easy manufacture, small weight, high strength and stability and excellent durability of the sashes and a neat appearance of the window even if equipped with a Venetian or other blind to be lowered and raised in the space between the glass panes. The construction is advantageous also by permitting easy renewal both of the blind and of the glass panes.

What I claim and desire to secure by Letters Patent is:

In a window structure for closing a window opening in the wall of a building for admission of light and air, comprising a rectangular frame to be mounted with two of its sides in vertical position and with its two other sides as bottom and top, respectively, of said frame, and a double sash composed of an inner sash mounted for swinging movement in said frame from shut position therein through an angle of about 180° about a horizontal median axis, and an outer sash mounted on said inner sash for swinging movement therewith and in relation thereto, the combination comprising each of said

inner and outer sashes being composed of a one-piece metal bar bent to U-shaped formation with rounded corners between its bottom portion and integral legs forming bottom and vertical sides, respectively, of the respective sash, and a straight sash top rail extending between the free ends of said legs and forming right angles with them and being detachably secured at its ends to said ends of said legs, each of said legs of said U-formation of said inner sash being pivoted intermediate its ends to one of the vertical sides of said frame, said detachable sash top rail having a depending flange for hiding a blind to be mounted on said inner sash top rail inside thereof and to be housed between said depending flange of said inner sash and said depending flange of said outer sash, said inner sash top rail being formed in the inside thereof and in spaced relation to said depending flange thereon with a groove for receiving a mounting bar for said blind, and each of said inner and outer sashes being provided in the inside of its U-formation and in the free edge portion of its said depending flange with recesses for receiving the edges of a glass pane, said detachable inner sash top rail having in cross section the shape of a hat section with crown and front and rear brim portions and with a veil hanging from the front end of the front brim portion and forming said depending flange of said inner sash top rail, and said outer sash top rail comprising a strip-shaped portion fitting over the portion of said inner sash top rail forming the rear brim portion of the hat section, a flange projecting upwards from one longitudinal edge of said strip portion for contact with the portion of said inner sash top rail forming the rear side of the crown of the hat section, and said depending flange of said outer sash top rail being provided on said strip-shaped portion adjacent the other longitudinal edge thereof.
